FOREIGN PATENT DOCUMENTS

GB 204750 * 4/2000

Primary Examiner — Karen E Eldridge Powers(74) *Attorney, Agent, or Firm* — Maier & Maier, PLLC(57) **CLAIM**

The ornamental design for a toothbrush, as shown and described.

DESCRIPTION

FIG. 1 is a front perspective view of a first embodiment of a toothbrush, showing my design;
 FIG. 2 is a right side elevation view thereof;
 FIG. 3 is a left side elevation view thereof;
 FIG. 4 is a front elevation view thereof;
 FIG. 5 is a rear elevation view thereof;
 FIG. 6 is a bottom plan view thereof;
 FIG. 7 is a top plan view thereof;
 FIG. 8 is a front perspective view of a second embodiment of a toothbrush, showing my design;
 FIG. 9 is a right side elevation view thereof;
 FIG. 10 is a left side elevation view thereof;
 FIG. 11 is a front elevation view thereof;
 FIG. 12 is a rear elevation view thereof;
 FIG. 13 is a bottom plan view thereof;
 FIG. 14 is a top plan view thereof;
 FIG. 15 is a front perspective view of a third embodiment of a toothbrush, showing my design;
 FIG. 16 is a right side elevation view thereof;
 FIG. 17 is a left side elevation view thereof;
 FIG. 18 is a front elevation view thereof;
 FIG. 19 is a rear elevation view thereof;
 FIG. 20 is a bottom plan view thereof; and,
 FIG. 21 is a top plan view thereof.
